TIE RACK

John L. Mack, Sr., Chicago, Ill.

Application August 30, 1946, Serial No. 693,951

5 Claims. (Cl. 211—100)

1

The present invention relates to tie racks, and has for its principal object the provision of a tie rack which may be hingedly supported on a wall, and which may be brought either to a horizontal or vertical position, in order that the same may conserve space when in a vertical position, and which may add to the suspended ties a maximum degree of display when the rack is brought to a horizontal position.

A still further object of the present invention is the provision, in conjunction with a tie rack of the type stated, of a plurality of rods journaled within a suitable supporting member, for the purpose of receiving therewithin individual ties, and which rods may freely rotate within the supporting member so as to conform to the changeable position of ties which the latter assume when the supporting member is shifted into a horizontal or vertical position.

Another object of the present invention is the provision of means in a garment supporting member for preventing its longitudinal movement with relation to a rack member within which the same is received.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views:

Fig. 1 is a face plan view of the tie rack when the same remains in a suspended vertical position;

Fig. 2 is a side elevational view of the tie rack when in a vertical position;

Fig. 3 is a cross-sectional view of line 3—3 of Fig. 1;

Fig. 4 is a side elevational view of the rack when the same remains in a horizontal position;

Fig. 5 is a longitudinal cross-sectional view of the tie rack when in a horizontal position;

Fig. 6 is a side elevational view of one of the rods employed in connection with the tie rack;

Fig. 7 is a face elevational view of the hinge member cooperating with the tie rack; and

Fig. 8 is a rear elevational view of the hinge member.

Referring in detail to the present drawing there is shown a hinge member, generally indicated by 10, and which includes a pair of side walls 11, and a pair of horizontal walls 12, the four walls

2

being arranged in a rectangular formation. Front wall 13, recessed as at 14, connects with said walls 11 and 12 at their front ends. Extending rearwardly from said wall 13, and from its marginal portion adjacent recess 14, is horizontal wall 15 and a pair of vertical walls 16. Said horizontal wall 15 is in a parallel relation with said horizontal walls 12, while said vertical walls 16 are in parallel relation with said walls 11.

10 Connecting with said vertical walls 16, and in a spaced, parallel relation with horizontal wall 15, is ledge 17. This ledge 17 terminates, however, short of said front wall 13.

Ledge 17 and bottom, horizontal wall 12 are 15 connected by connecting wall 18. Said bottom horizontal wall 12 is recessed along said vertical walls 16 and said connecting wall 18, for the purpose hereinafter stated.

From the hereinabove description it will be seen 20 that horizontal wall 15, vertical walls 16 and ledge 17 define a rectangular channel transversely of hinge member 10, while the front portions of said vertical walls 16, in conjunction with said connecting wall 18, define the recess which connects 25 with said channel, as is clearly seen in Figs. 3 and 5.

At a point substantially median of said channel as well as substantially median of the recess defined by said vertical walls 16 and connecting wall 30 18, a pin 19 is passed through and is mounted within said side walls 11 and said vertical walls 16 for the purpose hereinafter stated.

Two or more screws 20, passing through apertures 21, made in front wall 13 rigidly affix hinge 35 member 10 to any suitable fixture or wall 22.

The rack proper includes a pair of oblong plates 23, which adjacent one of their ends are recessed to define an oblong recess 24 within which pin 19 is receivable. Each of said plates 23 is further 40 provided with semi-cylindrical grooves 25, which are arranged transversely of said plates 23, grooves 25 in the two plates 23 being complementary to define cylindrical bores, within which central, cylindrical portion 26 of rods 27 are receivable and wherein they are freely journaled for rotation.

The ends of said rods 27 are of a larger diameter than said central portions 26 effecting shoulders 28, which bear against the adjacent edges 50 of plates 23, thereby preventing longitudinal movement of rods 27 within said plates 23.

Said ends of rods 27 are recessed as at 29, and terminate in laterally extending semi-annular flanges 30.

When rods 27 and pin 19 are in position within

two plates 23 thereupon said plates 23 are glued together or otherwise permanently affixed, for preventing the disengagement of the rack member from pin 19 and of rods 27 from the rack member.

Ties 31 may be inserted within recesses 29 of rods 27 when the rack member remains in a vertical position shown in Fig. 2. Since the two ends of ties 31 are disposed substantially along the two planes of rack member 23-23, when said rack member is shifted into a horizontal position shown in Figs. 4 and 5, one end of ties 31 will be carried by rods 22 due to their contact therewith, while the other ends thereof will hang from said rods, as is seen in Fig. 4. This action permits proper access to the ties at both of their ends, thereby facilitating display and selection of the ties.

When rack member 23-23 is in a vertical position pin 19 will remain at the end of recess 24 which is nearest to the adjacent end of the rack member, thereby suspending the rack member and supporting the same in a vertical position, as seen in Figs. 2 and 3. In that latter position rack member 23-23 fills the recess defined by said vertical walls 16 and connecting wall 18, with the front face of the rack member flush with said front wall 13.

When it is required that the rack be brought to a horizontal position illustrated in Figs. 4 and 5, the same is manually grasped and angularly shifted upon pin 19 substantially to 90 degrees, and when in that position the same is manually shifted into a longitudinal direction and into the channel defined by vertical walls 16, horizontal wall 15 and ledge 17, said walls snugly enclosing the adjacent end of the rack preventing the transverse shifting movement thereof, thereby rigidly holding and supporting the rack in a horizontal position. When in that latter position pin 19 will remain at the opposite end of said recess 24. Thus, said pin 19 constitutes means for limiting the movement of rack member 23-23 in either direction, and longitudinally of the rack member. A corner of outer plate 23 adjacent its outer face and at the end nearest to hinge member 10 is reduced and rounded as at 32 for providing clearance past the adjacent face of wall 15 when rack member is angularly shifted.

When rack member 23-23 is completely withdrawn from said channel defined by said vertical wall 16, horizontal wall 15 and ledge 17, the same will readily angularly shift upon pin 19, by gravity alone to assume vertical position. Connecting wall 18 constitutes a stop, preventing rack member 23-23 from further shifting when said connecting wall 18 comes in contact with the adjacent face on one of said plates 23, as seen in Fig. 3. Thus, it is impossible to bring or shift rack member 23-23 towards wall 22, due to the contact of connecting wall 18 with the rack member, thereby preventing marring of the wall or crumpling of ties 31 which would otherwise ensue if the rack member contacted wall 22.

Due to the fact that rods 27 are freely journaled within rack member 23-23 by their reduced portions 26, they are capable of rotary shifting movement during angular shifting of the rack member when ties 31 are suspended upon said rods and within recesses 29. Thus, due to tensioning action of ties 31 upon rods 27, when the rack member is in a vertical position, recess 29 will remain in a horizontal position. When, however, rack member 23-23 is shifted to a horizontal position, as seen in Fig. 4, rods 27 will make rotary shifting

movement to 90 degrees and their recesses 29 will assume vertical position as seen in Fig. 4. This rotary action of rods 27 is brought about by the tensioning and gravitational action of the downwardly extending ends of ties 31, due to the fact that said recesses 29 seek to assume vertical alignment in conformity with the downwardly hanging ends of ties 31, during the angular shifting movement of the rack member. By virtue of this arrangement ties 31 are prevented from winding around rods 27 during the angular shifting movement of rack member 23-23. Flanges 30 prevent slipping of the ties from the ends of rods 27 in a longitudinal, outward direction. The inner ends of recesses 29 being in a spaced relation with the edges of the rack member prevent portions of the ties which remain in said recesses 29 from contacting said rack member and thereby eliminate any interference by the ties with the operation of the rack member and rods 27.

While there is described herein a preferred embodiment of the present invention, it is nevertheless to be understood that minor changes may be made therein without departing from the spirit and scope of the invention as claimed.

What I claim as new is:

1. A tie rack comprising an oblong plate embodying a pair of complementary sections, each of said sections being provided with transverse, semi-cylindrical grooves, said grooves forming cylindrical bores when said sections remain in a face to face relation, cylindrical rods received within said bores for free rotation therewithin, the ends of said rods extending beyond the side edges of said plate and being provided with longitudinal recesses for receiving individual ties therewithin, and a hinge member to which said plate is pivoted for angular shifting movement.

2. A tie rack comprising an oblong plate embodying a pair of complementary sections, each of said sections being provided with transverse, semi-cylindrical grooves, said grooves forming cylindrical bores when said sections remain in a face to face relation, cylindrical rods received within said bores for free rotation therewithin, the ends of said rods extending beyond the side edges of said plate and being provided with longitudinal recesses for receiving individual ties therewithin, annular flanges at the free ends of said rods, said flanges preventing shifting of the ties longitudinally of said rods when the same remain within said recesses, and a hinge member to which said plate is pivoted for angular shifting movement.

3. A tie rack comprising a pair of complementary sections, each of said sections being provided with transverse, semi-cylindrical grooves, said grooves forming cylindrical bores when said sections remain in a face to face relation, cylindrical rods, each of said rods including reduced central portions received within said bores for free rotation therewithin, the enlarged ends of said rods defining shoulders bearing against the side edges of said sections preventing longitudinal shifting movement of said rods, the ends of said rods being provided with longitudinal recesses for receiving therewithin individual ties, and a hinge member to which said sections are pivoted for angular shifting movement.

4. A tie rack comprising a pair of complementary sections, each of said sections being provided with transverse semi-cylindrical grooves, said grooves forming cylindrical bores when said sections remain in a face to face relation, cylindrical rods, each of said rods including reduced

central portions received within said bores for free rotation therewithin, the enlarged ends of said rods defining shoulders bearing against the side edges of said sections preventing longitudinal shifting movement of said rods, the ends of said rods being provided with longitudinal recesses for receiving therewithin individual ties, annular flanges at the outer ends of said rods, said flanges preventing shifting of the ties longitudinally of said rods when the same remain within said recesses, and a hinge member to which said sections are pivoted for angular shifting movement.

5. A garment rack comprising a pair of complementary sections, each of said sections being provided with a transverse groove, the grooves in both sections forming a bore when said sections remain in a face to face relation, and a rod, said rod including a reduced central portion and enlarged end portions, said reduced central portion received within said bore, said enlarged end portions defining shoulders bearing against the edges

5

of said sections for preventing longitudinal shifting movement of said rod with relation to said sections, said enlarged end portions being adapted to support garments.
